United States Patent [19]

Smith

[11] Patent Number: Des. 283,439

[45] Date of Patent: ** Apr. 15, 1986

[54] ELECTROLYSIS MACHINE

[75] Inventor: Margaret M. Smith, Sylmar, Calif.

[73] Assignee: Clare, Inc., Sylmar, Calif.

[**] Term: 14 Years

[21] Appl. No.: 516,588

[22] Filed: Jul. 25, 1983

[52] U.S. Cl. D24/8

[57] CLAIM

The ornamental design for an electrolysis machine, substantially as shown.

DESCRIPTION

FIG. 1 is a front elevational view of the electrolysis machine showing my new design;
FIG. 2 is a side elevational view thereof;
FIG. 3 is a rear elevational view thereof;
FIG. 4 is a top plan view thereof; and
FIG. 5 is a bottom plan view thereof.

Fig. 1.

Fig. 2.

Fig. 3.

Fig. 4.

Fig. 5.
